UNITED STATES PATENT OFFICE.

BERNARD F. LAUKANDT, OF RED WING, MINNESOTA.

HARMONICA.

1,285,747.

Specification of Letters Patent. Patented Nov. 26, 1918.

Application filed July 3, 1918. Serial No. 243,137.

To all whom it may concern:

Be it known that I, BERNARD F. LAUKANDT, a citizen of the United States, residing at Red Wing, in the county of Goodhue 5 and State of Minnesota, have invented certain new and useful Improvements in Harmonicas, of which the following is a specification.

This invention relates to harmonicas or mouth organs provided with slidable mouthpieces; and it consists in the novel construction of the parts forming the mouthpiece as hereinafter fully described and claimed.

In the drawings, Figure 1 is a plan view 15 of a harmonica provided with a mouthpiece according to this invention. Fig. 2 is an end view of the same. Fig. 3 is a front view, and Fig. 4 is a partial rear view, of the harmonica. Fig. 5 is a cross-section through 20 the harmonica, taken on the line 5—5 in Fig. 3. Fig. 6 is a similar cross-section of the frame, but shows a modification.

The harmonica is of any approved construction, having a body portion 2 generally 25 formed of wood and provided with wind passages 3, metal reed plates 4, and vibrating reeds 5. Cover plates 6 are provided and are arranged above and below the body portion 2 and the reed plates. These cover 30 plates may be two separate cover plates as shown in Fig. 5, or they may be portions of a continuous cover 60 as shown in Fig. 6. The cover or cover plates have tone outlet holes or notches 7 at their rear parts.

35 The front edges of the cover plates 6 are provided with guide flanges 8 which project toward each other, and which are arranged parallel to the front edges 9 of the reed plates 4. The ends of the cover plates have 40 lugs 10 formed on them which are rigidly secured to the end portions of the body 2 of the instrument. The cover plates have also tongues 12 struck up from them and forming tone outlet holes 14. These tongues 45 bear on the reed plates and form distance pieces which accurately position the guide flanges 8 and prevent them from being sprung out of alignment by the pressure of the hand upon the cover plates.

50 Only two tongues are shown, but each cover plate may have as many of them as desirable. Openings 15 are formed at the ends of the cover plates between the ends of the guide flanges 8 and the lugs 10. The mouthpiece 16 is a block of any suitable 55 material, such as wood, hard rubber or alu-

minum. Its front edge may be straight, as shown, or it may be concave. This mouthpiece has wind passages 17, and its rear side slides against the front part of the body 60 portion and the edges 9 of the reed plates. The mouthpiece is provided with guide plates 18 having guide flanges 19 which project in opposite directions and engage with the flanges 8 of the cover plates. The harmonica and its mouthpiece may have a single row of wind passages, or said wind passages may be arranged one above another in a plurality of rows.

The flanges 19 slide through the openings 70 15, as indicated by dotted lines in Fig. 1, and they have stops 20 which engage with the lugs 10 and limit the travel of the mouthpiece in each direction, and prevent it from being wholly separated from the instrument. 75

The mouthpiece is held between the lips in the usual way, and the harmonica is slid back and forth upon it in playing the instrument. The rubbing contact between the instrument and the lips is obviated, and the 80 construction of the attachment is such that a very free and frictionless contact is provided between the mouthpiece and the instrument, and the device is very inexpensive to manufacture. The mouthpiece can also 85 be made of celluloid.

What I claim is:

1. The combination, with a harmonica body, of cover plates secured above and below the harmonica body and having guide 90 flanges at their front edges, distance pieces arranged between the cover plates and the harmonica body, and a mouthpiece slidable against the front of the harmonica body and provided with guide flanges which engage with the aforesaid guide flanges.

2. The combination, with a harmonica body, of cover plates secured above and below the harmonica body and having guide flanges at their front edges, said cover plates 100 having also tongues struck up from them and forming tone outlet holes, said tongues bearing against the instrument and positioning the said guide flanges, and a mouthpiece slidable against the front of the harmonica 105 body and provided with guide flanges which engage with the aforesaid guide flanges.

3. The combination, with a harmonica having reed plates above and below its body portion, of cover plates secured above and 110 below the reed plates and having guide flanges at their front edges, distance pieces

between the said cover plates and reed plates, a mouthpiece slideable against the front part of the instrument, and guide flanges secured to the mouthpiece and engaging with the 5 aforesaid guide flanges.

4. The combination, with a harmonica body, of cover plates secured above and below the harmonica body and having guide flanges at their front edges and having also 10 lugs at their ends for securing them to the harmonica body, openings being formed be-

tween the said flanges and lugs, distance pieces between the cover plates and the harmonica body, and a slideable mouthpiece provided with guide flanges which slide through 15 the said openings and engage with the aforesaid guide flanges and which have projecting stops which engage the lugs.

In testimony whereof I have affixed my signature.

BERNARD F. LAUKANDT.
